(57) **CLAIM**

The ornamental design for a heater, as shown and described.

DESCRIPTION

Cross reference is made to copending U.S. design patent application ser. no. 29/592,758 entitled "Heater" by Fritz et al. filed on even date herewith.

FIG. 1 is a perspective view of a heater showing our new design;

FIG. 2 is a front elevational view of the heater of FIG. 1;
FIG. 3 is a rear elevational view of the heater of FIG. 1;
FIG. 4 is a left side elevational view of the heater of FIG. 1;
FIG. 5 is a right side elevational view of the heater of FIG. 1;

FIG. 6 is a top plan view of the heater of FIG. 1; and,
FIG. 7 is a bottom plan view of the heater of FIG. 1.

The broken lines shown in the drawings illustrate portions of the heater that form no part of the claimed design.
